TREATMENT OF TOPICAL VIRAL INFECTIONS
WITH GLUCOCORTICOIDS AND NUCLEOSIDES
Gerald E. Underwood, Galesburg, Mich., assignor to The
Upjohn Company, Kalamazoo, Mich., a corporation of
Delaware
No Drawing. Filed June 8, 1964, Ser. No. 373,501
3 Claims. (Cl. 167—58)

This application is a continuation-in-part of copending application Ser. No. 296,095, filed July 18, 1963, now abandoned.

This invention relates to pharmaceutical preparations, more particularly pharmaceutical preparations adapted for topical pharmaceutical applications.

The preparations of the instant invention are advantageously useful in topical pharmaceutical applications to mammals, for they demonstrate unexpected activity in ophthalmic disorders as shown by their effectiveness in treating herpetic conditions in the eyes. The pharmaceutical application of glucocorticoids in such conditions is widespread but often hazardous and accompanied by deleterious side effects. Secondary encephalitis is a hazard of such application and can result in death. Perforation does not occur during such application in disciform keratitis. Keratitis profunda and keratouveitis sometimes occur during or following glucocorticoid applications. Prolonged persistence of herpes simplex virus in the cornea often occurs. Moreover, glucocorticoids are known to mask progress of herpetic conditions in the eye whereby infection progresses despite apparent improvement of the eye. It has now been found that the pharmaceutical preparations of the instant invention unexpectedly minimize or abolish such hazards and deleterious side effects while providing beneficial effectiveness in treating herpetic involvement. Other beneficial topical pharmaceutical applications to mammals are in viral skin lesions of vaccinia and herpes simplex.

In accordance with the present invention, there are provided pharmaceutical preparations comprising in combination a topical anti-inflammatory glucocorticoid and a topical antiviral nucleoside. Suitably, topical pharmaceutical means which adapt the preparations for topical pharmaceutical applications are added to the combination.

The term "topical anti-inflammatory glucocorticoid" means steroids of natural and synthetic origin which demonstrate topical anti-inflammatory properties; for example, cortisone acetate, dexamethasone, dexamethasone phosphate sodium, fludrocortisone acetate, fluorometholone, hydrocortamate hydrochloride, hydrocortisone, hydrocortisone acetate, methylprednisolone, methylprednisolone acetate, prednisolone, prednisolone phosphate sodium, and triamcinolone acetonide. The term "topical antiviral nucleoside" means those nucleosides demonstrating beneficial activity in the treatment of viral ophthalmic conditions and viral skin lesions. The antiviral nucleosides are arabinofuranosyl nucleosides of uracil and cytosine and are selected from the group consisting of 1- β -D-arabinofuranosyluracil, its 5-bromo, -chloro, -fluoro, -iodo, and -methyl derivatives, 1- β -D-arabinofuranosylcytosine, its 5-methyl derivative, and the pharmaceutically acceptable acid addition salts thereof, such as the hydrochloride, citrate, succinate and tartrate. "Topical pharmaceutical means which adapt the preparation for topical pharmaceutical applications" means lotion vehicles; ointment bases; cream bases; hydrogel pastes; fatty pastes; aqueous solutions, preferably isotonic, especially buffered ophthalmic solutions containing a surfactant such as polysorbate 80 and p-isoocytyl polyoxyethylene phenol (Triton WR-1339); aqueous suspending vehicles;

2

micronized diluents; propellant-containing liquid vehicles adapted to form an aerosol; and the like. Any utilized means preferably makes up a major amount of the weight or volume of the preparation. Such topical pharmaceutical means preferably are sterile and contain a nontoxic bactericidal or bacteriostatic agent.

The topical anti-inflammatory glucocorticoid and the topical antiviral nucleoside are the essential active ingredients. They are preferably micronized. However, nontoxic antibacterial agents, preferably topically effective antibiotics such as neomycin, polymycin, and bacitracin, can be added to control any secondary bacterial infections.

The percentage of the topical anti-inflammatory glucocorticoid ranges from about 0.025% to about 2.5% of the preparation. The percentage in a liquid vehicle adapted for aerosol formation varies from about 0.01% to about 0.3%. The percentage of the antiviral component ranges from about 0.1% to about 10% within which the preferred range is from about 0.5% to about 2%.

The following examples describe the manner and process of making and using the invention and set forth the best mode contemplated by the inventor of carrying out in the invention but are not to be construed as limiting.

25 Treatment of rabbit eyes infected with herpes simplex virus demonstrates beneficial unexpected activity of the novel topical pharmaceutical preparation.

Herpes simplex virus was isolated from a herpetic lip lesion and was subjected to 8 passages in rabbit kidney 30 cell cultures. A titer of approximately 10^8 plaque forming units per milliliter was obtained. A culture of this titer was used undiluted for infecting rabbit eyes by rubbing the cornea thoroughly with a cotton swab saturated with the culture. 16 rabbits were so infected in all eyes 35 and separated into 4 groups of 4 rabbits each.

CONTROL GROUP

40 42 hours after infection, treatment of all eyes in this group was started with a sterile ointment composed of wool fat, liquid petrolatum and white petrolatum with 0.5% of neomycin sulfate as antibacterial agent to prevent secondary infection. The treatment was continued every hour from 8 a.m. to 5 p.m. for six consecutive days.

45 ANTI-INFLAMMATORY GLUCOCORTICOID GROUP

42 hours after infection, treatment of all eyes in this group was started with a sterile ointment composed of 50 wool fat, liquid petrolatum, white petrolatum, 0.5% neomycin sulfate as antibacterial agent to prevent secondary infection and 1.5% of hydrocortisone acetate. The treatment schedule was identical to that for the control group.

55 TOPICAL ANTIVIRAL NUCLEOSIDE GROUP

A sterile ointment was compounded of wool fat, liquid petrolatum, white petrolatum, 0.5% of neomycin sulfate 60 as antibacterial agent to prevent secondary infection and 1% of 1- β -D-arabinofuranosylcytosine hydrochloride. The treatment schedule was identical to that for the control group.

65 *Example 1.—Combination of glucocorticoid and nucleoside*

A sterile ointment was compounded of wool fat, liquid petrolatum, white petrolatum, 0.5% of neomycin sulfate 70 as antibacterial agent to prevent secondary infection, 1.5% of hydrocortisone acetate, and 1% of 1- β -D-arabinofuranosylcytosine hydrochloride. The same treatment regimen was followed.

METHOD OF OBSERVING AND RECORDING
RESULTS

Each eye was observed daily with the aid of an ophthalmoscope to ascertain the degree of herpetic involvement, which was recorded as

5

-, +, +, and + dissolved therein. The solution is made isotonic with sodium chloride buffered at a pH of 7.4 and sterilized by passage through a bacteria retaining filter. The sterile solution and a compatible nontoxic liquefied propellant are packaged in a container to provide a solution adapted

-, +, +, and +

the latter showing deep stromal involvement with cloudy cornea. In the following recapitulation the digits represent the number of observed eyes.

10 to form an aerosol. Equally beneficial unexpected results are obtained therefrom in topical application to monkey eyes infected with herpes simplex virus.

Treatment Group	Day 2 of Treatment				Day 4 of Treatment				Day 6 of Treatment				Day 2 Post Treatment			
	-	+	-	+	-	+	-	+	-	+	-	+	-	+	-	+
Control	8	4	1	0	0	0	3	5	0	0	1	7	0	0	2	6
Glucocorticoid	4	4	0	0	0	1	7	0	0	0	4	4	0	0	2	4
Nucleoside	8	0	0	0	8	0	0	0	7	1	0	0	7	1	0	0
Example 1	8	0	0	0	7	1	0	0	7	0	1	0	5	1	1	1

Treatment Group	Day 4 Post Treatment				Day 6 Post Treatment				Day 9 Post Treatment				Day 14 Post Treatment			
	-	+	-	+	-	+	-	+	-	+	-	+	-	+	-	+
Control	1	2	0	5	4	0	2	2	2	0	4	2	3	3	2	0
Glucocorticoid	1	-	-	3	-	1	-	1	-	1	-	1	1	-	1	1
Nucleoside	4	(2 dead)	1	0	3	0	5	0	3	1	4	0	5	2	1	0
Example 1	3	2	1	1	4	3	0	1	5	2	0	1	5	2	1	1

The data show that the glucocorticoid-nucleoside combination product of Example 1 effectively controls the herpetic involvement and prevents the deleterious side effects of the glucocorticoid.

Example 2.—Combination of glucocorticoid and nucleoside

An aqueous lotion vehicle is prepared. 0.5% by weight of 1- β -D-arabinofuranosylcytosine HCl and 0.1% by weight of dexamethasone phosphate sodium are dissolved therein. The solution is made isotonic with NaCl and sterilized by passage through a bacteria-retaining filter. The sterile solution is used in topical pharmaceutical applications to monkey eyes infected with herpes simplex virus. Equally beneficial unexpected results to those with Example 1 are obtained. The deleterious effect of the corticosteroid is ameliorated by treatment with the combination.

Example 3.—Combination of glucocorticoid and nucleoside

A topical cream base is prepared. 0.5% of micronized prednisolone and 5.0% of micronized 1- β -D-arabinofuranosylcytosine are incorporated therein. The cream is used in topical pharmaceutical applications to rabbit eyes infected with herpes simplex virus. Equally beneficial unexpected results to those with the previous examples are obtained.

Example 4.—Combination of glucocorticoid and nucleoside

A sterile topical ointment base is prepared. 0.1% of sterile methylprednisolone and 10.0% of sterile 1- β -D-arabinofuranosylcytosine are incorporated therein. The sterile preparation is used in topical pharmaceutical applications to rabbit eyes infected with herpes simplex virus. Equally beneficial unexpected results to those with the previous examples are obtained.

Example 5.—Combination of glucocorticoid and nucleoside

An aqueous lotion vehicle is prepared. An amount of triamcinolone acetonide equivalent to 1 mg. per ml. of the vehicle and an amount of 1- β -D-arabinofuranosylcytosine hydrochloride equivalent to 25 mg. per ml. are

Example 6

35 A topical cream base is prepared. 0.025% by weight of micronized fluorometholone, 2% by weight of micronized 1- β -D-arabinofuranosylcytosine and 0.5% of neomycin sulfate are incorporated therein. The cream is used in topical pharmaceutical applications to rabbit eyes infected with herpes simplex virus. Equally beneficial unexpected results to those with the previous examples are obtained.

Example 7.—Combination of glucocorticoid and nucleoside

45 A finely divided powder for topical pharmaceutical applications is prepared by blending 80 parts by weight of micronized 1- β -D-arabinofuranosylcytosine hydrochloride and 1 part by weight of micronized fluorometholone. The powder is applied topically with beneficial results in herpes simplex skin lesions in rabbits and vaccinia 50 skin lesions in monkeys.

Example 8.—Other combinations of glucocorticoid and nucleoside

55 Pharmaceutical preparations combining the following concentrations of glucocorticoid and nucleoside are prepared with topical pharmaceutical means.

	Percent
Cortisone acetate	0.5 to 2.5
Fludrocortisone acetate	0.05 to 0.25
Hydrocortamate hydrochloride	0.5
Hydrocortisone acetate	0.5 to 2.5
Methylprednisolone acetate	0.25 to 1.0
Prednisolone phosphate sodium	0.25 to 0.5
1- β -D-arabinofuranosyl-5-bromouracil	1
5-chloro derivative of this nucleoside	2
5-fluoro derivative of this nucleoside	5
5-iodo derivative of this nucleoside	10
5-methyl derivative of this nucleoside	2
1- β -D-arabinofuranosyluracil HCl	1
5-methyl derivative of 1- β -D-arabinofuranosylcytosine	1

These combinations are prepared preferably with the said topical pharmaceutical means to provide preparations which are also beneficial in topical pharmaceutical applications.

The 5-halo derivatives of 1- β -D-arabinofuranosyluracil are prepared by direct halogenation by reacting the parent compound with, for example, chlorine, bromine and iodine in the presence of an inert solvent which can be aqueous or nonaqueous. The inert solvent depends on the particular halogen, for example, chlorination in a mixture of acetic acid and carbon tetrachloride, bromination in water alone. The halo compounds are recovered by removing excess halogen, evaporating the volatile components, solvent extraction and crystallization. See Ser. No. 51,301 filed Aug. 23, 1960. Brown et al., Chem. Soc. J. 2388-2393 (July) 1956 describes 3- β -D-arabinofuranosyluracil (1 - β - D-arabinofuranosyluracil). The procedure of Fox et al., J.A.C.S., 79, 2775-2778 (1957) yields the 5-methyl derivative, also known as phongothymidine. Walwich et al., Proc. Chem. Soc., 84 (March), 1959 describes 3- β -Darabinofuranosylcytosine (1- β -D-arabinofuranosylcytosine). Its 5-methyl derivative is described in U.S. 3,116,282.

What is claimed is:

1. A process for minimizing deleterious effects of topical anti-inflammatory glucocorticoids in topical viral infections which comprises application to the infected area of a pharmaceutical preparation comprising in combination
  - (a) from about 0.025% to about 2.5% of a topical anti-inflammatory glucocorticoid,
  - (b) from about 0.1% to about 10% of a topical anti-viral nucleoside selected from the group consisting of 1 - β - D - arabinofuranosyluracil, its 5-bromo,

20

30

-chloro, -fluoro, -iodo, and -methyl derivatives, 1- β -D-arabinofuranosylcytosine, its 5-methyl derivative, and pharmaceutically acceptable acid addition salts thereof, and

- (c) topical pharmaceutical means which adapt the preparation for topical pharmaceutical application.
2. The process of claim 1 wherein the topical antiviral nucleoside is present in an amount of from about 0.5% to about 2%.
3. The process of claim 2 wherein the 1- β -D-arabinofuranosylcytosine hydrochloride is present in an amount of about 1%.
